LIONEL POIRIER AND VICTOR VARIN, OF CHICOPEE FALLS, MASSACHUSETTS

BLUING HOLDER

Application filed February 9, 1932. Serial No. 591,877.

The invention relates to a holder and more especially to a blueing holder.

The primary object of the invention is the provision of a holder of this character where 5 in a group or series of capsules are supported and these contain blueing so that a determined quantity of the latter corresponding to the capacity of an individual capsule can be delivered to water for washing purposes, the capsules being arranged 10 in a row upon a backing that may be detachably held upon a suitable support for convenient and free accessibility.

Another object of the invention is the provision of a holder of this character, wherein the construction thereof is novel in form as determined quantities of blueing are carried in capsules, these being grouped and held upon a backing so that the quantities 20 of blueing are ready for use during clothes washing periods.

A further object of the invention is the provision of a holder of this character which is extremely simple in construction, thoroughly reliable and efficient in its purpose, neat in appearance, holding blueing in determined quantities ready for use, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:—

Figure 1 is a perspective view of the holder constructed in accordance with the invention and showing one section of the capsules detached and in pouring position for the dispensing of the blueing therein.

Figure 2 is a longitudinal sectional view through the holder, the same being mounted upon a support or wall, and one of the capsules shown in section.

Similar reference characters indicate corresponding parts throughout the several views in the drawing.

Referring to the drawing in detail, the

holder comprises a backing 5 preferably made from stiff cardboard of the required thickness and of flat strip formation having either rounded or squared ends, it being understood of course that said backing may be otherwise made from any suitable material. Medially of this backing is attached through the medium of a rivet 7 a suction cup 8 so that the said backing may be attached to a support or wall A as shown in Figure 2 of the drawing for the hanging thereof in position for use.

The backing has anchored at its outer end thereto a series, group or row of spaced gelatine capsules 9, each including a separable outer section or part 10 which is telescoped into the other section thereof, these capsules 9 being preferably anchored in spaced relation to each other upon the backing 5 through the medium of adhesive 11 and in a straight row.

The capsules contain a determined quantity of blueing 12 to be dispensed into water during the washing of clothes or other articles.

It will be apparent that when it is desired to deliver to a quantity of water blueing substance it is only necessary to remove the section 10 of the capsules which contain a determined amount of blueing 12 and the same is thrown or deposited within the water where the powdered blueing is instantly dissolved therein with the gelatine part 10 of the capsules.

It should be obvious that the holder is mountable in a convenient place by the cup 8 so that the holder will be hung upon a support for the use of said holder in the holding and the handling of the blueing substance contained within the respective capsules constituting a part of the holder.

What is claimed is:—

1. A holder of the character described comprising a backing having a plurality of capsules anchored thereon and containing blueing substance, the outermost part of each capsule being separable for the dispensing of the blueing substance held therein, and means for detachably fastening the backing to a support.

2. A holder of the character described comprising a backing having a plurality of capsules anchored thereon and containing blueing substance, the outermost part of each capsule being separable for the dispensing of the blueing substance held therein, and a suction cup carried by said backing.
3. A holder of the character described comprising a backing, a capsule anchored upon the backing and having a removable section, blueing contained within the capsule, and a suction cup on the backing for the detachable mounting thereof upon a support.

In testimony whereof we affix our signatures.

VICTOR VARIN.
LIONEL POIRIER.
